UNITED STATES PATENT OFFICE.

THOMAS E. PECK AND FRANK W. HARRISON, OF SIOUX CITY, IOWA.

HOG OILER.

Application filed June 26, 1925. Serial No. 39,648.

To all whom it may concern:

Be it known that we, THOMAS E. PECK and FRANK W. HARRISON, citizens of the United States, and residents of Sioux City, 5 in the county of Woodbury and State of Iowa, have invented certain new and useful Improvements in a Hog Oiler, of which the following is a specification.

Our invention relates to a hog oiler, and 10 has for its object primarily to provide an oiler which will spray the backs of hogs passing through a gateway forming a part of the invention.

More particularly, our invention is embodied in a structure in which a nozzle for spraying oil depends from the top of a gateway, in which is hinged at its upper edge a gate, adapted to actuate by its swinging, a valve which controls the flow of oil to the 20 nozzle, and a pump being provided to force the oil under pressure from a suitable tank through the valve and to the nozzle.

Another object is to provide such a structure in which a pair of nozzles may be used, 25 one located on either side of the gate, together with a two-way valve, so actuated by the swinging of the gate that when the gate is depending the valve will be closed, and when the gate is swung to either side the 30 valve will open the pipe line to the nozzle on the other side of the gate.

Another object is to provide such a structure having a frame supporting the oil-spraying mechanism, and which is adapted 35 to be readily inserted in an opening provided for it in a hog fence.

With these and other objects in view our invention consists in the construction, arrangement and combination of the various 40 parts of our device, whereby the objects contemplated are attained, as hereinafter more fully set forth, pointed out in our claims, and illustrated in the accompanying drawings, in which:

45 Fig. 1 is a front elevation of the oiler.

Fig. 2 is a side elevation of the same.

Fig. 3 is a horizontal transverse sectional view taken on the line 3—3 of Fig. 1.

Fig. 4 is a detail horizontal sectional view 50 through the valve.

Fig. 5 is a detail vertical sectional view illustrating the connection of the valve shaft to the pinion spindle, which actuates the valve.

55 Fig. 6 is a detail view of the valve pinion actuating gear.

Fig. 7 is a sectional view through the same, taken on the line 7—7 of Fig. 6.

Fig. 8 is a detail sectional view, taken on 60 the line 8—8 of Fig. 7.

Fig. 9 is a detail sectional view, taken on the line 9—9 of Fig. 7.

Most of the hog oilers which have been devised aim to distribute oil to the side of a hog by rubbing contact of the hog with a 65 suitably disposed rotating drum mounted in some manner to receive oil at its periphery. Such devices usually are not efficient in distributing oil to the back of the hog, where it is most needed, and the present invention 70 contemplates spraying the oil on the back of a hog from whence it will work its way onto the sides.

The oiler has a gateway frame, 10, of 75 angle iron, which is adapted to be inserted in a suitable gateway of wooden studding or the like, formed for the purpose in a hog fence, as indicated in dotted lines at 11 in Fig. 3. In bearings, 12 and 13, secured to the frame, 10, is mounted a horizontal shaft, 14, which extends at one end through the side of the frame, 10, in order to receive the actuating mechanism, which will be later described herein.

A gate, 15, which may be of sheet metal 85 or wood is secured by means of yokes, or the like, 16, to the shaft, 14, so that swinging of the gate will cause the shaft to oscillate. An oil tank, 17, may be supported in any suitable position from the gateway, as 90 by brackets, 18, securing it to the upper side thereof.

A pump cylinder, 19, is supported by means of brackets, 20, on the side of the frame, 10, and a tube, 21, connects the upper end of said cylinder to the tank, 17. A check valve, 22, of ordinary construction is inserted between the tube, 21, and the pump cylinder, 19, so as to check the flow of oil from the pump cylinder back to the 100 tank, 17, and to allow flow of oil from the tank, 17, to the pump cylinder.

A short tube, 23, communicating with the upper end of the pump cylinder through the medium of a similar check valve, 24, communicates with and serves to support a two-way valve, 25. The valve, 25, has the entranceway, 26, and the two exit passages, 27 and 28, respectively.

The tube, 23, is threaded into the passage, 110 26, and the tubes, 31 and 32, are threaded into the passages, 27 and 28, respectively.

The discharge tubes, 31 and 32, are extended upwardly, as at 33, to a plane just above the shaft, 14, and are thence bent laterally and crossed, as at 34, in the space above the door, 15, and below the frame, 10.

At the point where the tubes, 31 and 32, cross, they are suspended by a bracket, 35, in the frame, 10. The ends of the tubes are bent downwardly as at 36 on either side of the gate, 15, and are provided with nozzles, 37 and 37^a.

The valve, 25, is adapted to establish communication between the tubes, 23 and 31, or 23 and 32, when the gate, 15, is swung in either direction in order that oil may be delivered to the proper nozzle, 37. For this purpose we provide a valve-actuating means as follows.

The bearing, 13, is formed as part of a bracket, having an ear, 38, by means of which the bracket is secured to the frame side member, 10, and having an arm, 39, bent outwardly parallel to the shaft, 14, and spaced thereunder. The end of the arm, 39, is provided with a bearing, 40, in which is journaled the spindle, 41, of a pinion, 42. The pinion, 42, and spindle, 41, are formed integrally, and to the lower end of the spindle, 41, is secured a socket, 43, having a squared opening which receives the squared shank, 44, of the valve core, 29.

The core, 29, extends vertically through the valve casing at the juncture between the three passages, 26, 27 and 28, so as to separate them. The core, 29, has an arcuate cavity, 30, which is of such width that when the core is in neutral position, as shown in Fig. 4, the passages, 27 and 28, will be entirely closed by the remainder of the valve core, the opening, 30, being positioned registering with the passage, 26.

The movement of the valve core, 29, through an arc of 45 degrees to either side of neutral position shown in Fig. 4, will establish communication between the passage, 26, and one of the passages, 27 or 28, the other passages remaining closed. These two positions of the valve core are indicated in dotted lines in Fig. 4.

Before proceeding further, it may be stated generally that the mechanism is so arranged that the valve, 25, will open rapidly when the gate, 15, commences to swing in either direction and thereafter when the valve has already established communication between the proper channels, oil will be pumped from the cylinder, 19, through the discharge channel, which has been opened. In order that the valve may be opened rapidly and maintained in either of its full open positions illustrated in Fig. 4 in dotted lines, we provide the following mechanism.

The pinion, 42, has an upper conical face, 45, in which are cut two gear teeth, 46, and a lower cylindrical face, 47, which is cut

away to form a wedge-shaped nose, 48, positioned directly below the teeth, 46.

To the shaft, 14, is secured a gear comprising a disk, 49, having an annular plane rim, 50, and three crown gear teeth, 51, formed adjacent and within the rim, 50. A depression, 52, is formed adjacent the teeth, 51, in the rim, 50, and receives the wedge-shaped nose, 48, of the pinion, 42. The teeth, 46, mesh with the crown teeth, 51, of the gear, and the flattened side faces, 53, are adapted to slide against the rim, 50, of the rim after the gear has rotated to a position where the teeth, 46 and 51, no longer mesh.

The gear is of such size that upon swinging of the gate 15, and resulting oscillation of the shaft, 14, the rotation of the gear will rapidly revolve the pinion, 42, to a position where the valve, 25, will be open, and thence the flat face, 53, which is in contact with the rim, 50, will lock the pinion in the correct position to maintain the valve in full open position. When the gate is in vertical depending position, the gear teeth, 51, will be in the bottom of the gear and the nose, 48, of the pinion will be received within the depression, 52, of the gear.

The operation of the pump is designed to proceed at a rate varying inversely to that of the operation of the valve. That is, its piston commences to move slowly and thereafter moves more rapidly. In order to effect this, we provide a crank arm, 54, secured to the outer end of the shaft, 14. A piston, 55, is carried on the inner end of a piston rod, 56, slidably extended through a packing gland, 57, in the end of the pump cylinder, 19. A connecting rod, 58, is hingedly secured to the crank arm, 54, and piston rod, 56, so that as the crank arm, 54, moves in an arc with the oscillation of the shaft, 14, the connecting rod, 58, will move up and down with a harmonic motion, and correspondingly move the piston, 55, commencing slowly and increasing in speed as it moves upwardly.

The check valve, 24, allows flow of the oil from the pump cylinder, 19, to the valve, 25, and checks the flow of oil in a reverse direction.

It will now be seen that as a hog proceeds through the gateway in the direction indicated by the arrow, 59, in Fig. 2, and swings the gate in that direction, the gear, 49, will be rotated as indicated by the arrow, 60, in Fig. 2, and the pinion, 42, will be rotated as indicated by the arrow, 61, in Fig. 9. Correspondingly the valve core, 29, will be rotated as indicated by the arrow, 62, in Fig. 4, and the cavity, 30, will be brought to the dotted line positions indicated by the arrow, 63, in Fig. 4. Communication will then be established between the tubes, 23 and 31, and the pump will thereafter force

oil from the cylinder, 19, upwardly through the tubes, 23 and 31, to the nozzle, 37, which depends over the gateway on that side of the gate from which the hog is proceeding.

5 The parts are so arranged that the spray of oil will commence when the shoulders of the hog are directly under the nozzle, 37, and continue until the oil has been distributed along the majority of the length of 10 the hog's spine. When the hog moves in the other direction the nozzle, 37^a, will act.

As the pump piston, 55, moves downwardly with the return swing of the gate, oil will be drawn in through the tube, 21, from the 15 tank, 17.

The crank arm, 54, is secured in the shaft, 14, by threaded nuts, 54^a, by adjustment of which the throw of the arm may be lengthened or shortened. The stroke of the piston 20 in the cylinder may thus be varied. When so adjusting, the length of the cylinder will allow the added movement of the piston caused by the lengthening of the crank arm.

In order to check the swing of the gate 25 beyond center on its return swing, we provide a U-shaped keeper, 65, which is pivoted to the frame by means of a bolt, 66. A coil spring, 67, serves to impose tension on the bolt, 66, and thence upon the keeper. The 30 coil spring is received over the bolt and when the oiler is installed in a gateway of a fence, the spring will be compressed between the outer end of the bolt and the outer face of the joist, 11. A hole may be bored 35 in the joist to receive the bolt. A slot is provided in the joist on the other side of the gateway to receive the shaft, 14.

The lug, 68, secured to the gate, 15, is so positioned as to normally be received between the arms of the keeper, 65. As the 40 gate swings in one direction the keeper will be tilted to that side, remaining there to receive the lug as the gate swings back to center.

45 Some changes may be made in the construction and arrangement of the parts of our invention without departing from the real spirit and purpose of our invention, and it is our intention to cover by our claims 50 any modified forms of structure or use of mechanical equivalents which may be reasonably included within their scope.

We claim as our invention:

1. In a hog oiler, a gateway, a gate hinged 55 therein at its upper edge for swinging movement laterally of the gateway in either direction, an oil reservoir, a pair of oil discharge pipes having their discharge ends positioned one on either side of the gate, a two-way valve having a connection with the oil reservoir and with the discharge pipes, means controlled by the swinging of the gate for actuating said valve to allow flow of oil from the reservoir to the discharge 60 pipe away from the discharge end of which

the gate is swung, and means actuated by the swinging of the gate to pump the oil from the reservoir to said two-way valve.

2. In a hog oiler, a gateway, a gate hinged 70 therein at its upper edge for swinging movement laterally of the gateway, an oil reservoir, an oil discharge pipe, a valve having a connection with said reservoir and said discharge pipe, means controlled by the swinging of the gate for actuating said valve to allow flow of oil from the reservoir to the discharge pipe when the gate is swung laterally from the gateway, and means actuated by the swinging of the gate to pump the oil 75 from the reservoir to said valve.

3. In a hog oiler, a gateway, a gate hinged 80 therein at its upper edge for swinging movement laterally of the gateway in either direction, an oil reservoir, a pair of oil discharge pipes having their discharge ends 85 positioned one on either side of the gate, a two-way valve having a connection with the oil reservoir and with the discharge pipes, and means controlled by the swinging of the gate for actuating said valve to allow flow of 90 oil from the reservoir to the discharge pipe away from the discharge end of which the gate is swung.

4. In a hog oiler, a gateway, a gate hinged 95 therein at its upper edge for swinging movement laterally of the gateway in either direction, an oil reservoir, an oil discharge pipe having its discharge end positioned over the gateway, a valve having a connection with the oil reservoir and with the discharge pipe, and means controlled by the 100 swinging of the gate for actuating said valve to allow flow of oil from the reservoir to the discharge pipe.

5. In a hog oiler, a gateway, a shaft journaled in a horizontal position in the gateway, a gate secured at its upper edge to said shaft, a crank arm on the shaft, an oil reservoir, an oil discharge pipe having its discharge end positioned over the gateway, 110 means actuated from said crank arm for pumping oil from the reservoir through said oil discharge pipe, a valve in said oil discharge pipe, and a valve actuating member secured to the shaft and linked with the 115 valve so as to open said valve when the gate is swung away from vertical position.

6. In a hog oiler, a gateway, a shaft journaled in a horizontal position in the gateway, a gate secured at its upper edge to said 120 shaft, a crank arm on the shaft, an oil reservoir, an oil discharge pipe having its discharge end positioned over the gateway, means actuated from said crank arm for pumping oil from the reservoir through said oil discharge pipe, a valve in said oil discharge pipe, a valve stem, a pinion thereon, and a gear on the shaft meshing with said pinion so as to open said valve when the gate 125 is swung away from vertical position.

7. In a hog oiler, a gateway, a gate hinged therein at its upper edge for swinging movement laterally of the gateway in either direction, an oil reservoir, an oil discharge pipe having its discharge end positioned over the gateway, a valve having a connection with the oil reservoir and with the discharge pipe, and means controlled by the swinging of the gate for actuating said valve to allow flow of oil from the reservoir to the discharge pipe, said means being adapted to rapidly open the valve during the lower portion of the arc of swing of the gate, and to thereafter maintain the valve in open position during the upper portion of the arc of swing of the gate.
8. In a hog oiler, a gateway, a shaft journalled in a horizontal position in the gateway, a gate secured at its upper edge to said shaft, a crank arm on the shaft, an oil reservoir, an oil discharge pipe having its dis-

charge end positioned over the gateway, means actuated from said crank arm for pumping oil from the reservoir through said oil discharge pipe, a valve in said oil discharge pipe, a valve stem, a pinion thereon, and a gear having a limited number of teeth in engagement with said pinion, the gear being provided with a cam face and the pinion being provided with a coacting face adapted to engage with said cam face when the pinion has been rotated to the extent of its meshing with the gear teeth, whereby the pinion will be maintained immovable during a portion of the arc of swing of the gate, and rapidly actuated during the remainder of the arc of swing thereof.

Signed at Sioux City, in the county of Woodbury and State of Iowa, this 22nd day of June, 1925.

THOMAS E. PECK.
FRANK W. HARRISON.
